UNITED STATES PATENT OFFICE

JOHN J. DALY, OF WEST NEWTON, MASSACHUSETTS, ASSIGNOR TO SPENCER CHAIN STORES, INC., OF MALDEN, MASSACHUSETTS, A CORPORATION OF MASSACHUSETTS

DESIGN FOR A STORE FRONT

Application filed November 11, 1929. Serial No. 33,412. Term of patent 14 years.

To all whom it may concern:

Be it known that I, JOHN J. DALY, a citizen of the United States, residing at West Newton, in the county of Middlesex and State of Massachusetts, have invented a new, original, and ornamental Design for Store Front, of which the following is a specification, reference being had to the accompanying drawing, forming part thereof.

Fig. 1 is a front perspective view of a store front, showing my new design, and

Fig. 2 is a horizontal midsection in diagrammatic outline and on a somewhat reduced scale.

I claim:

The ornamental design for a store front, as shown.

JOHN J. DALY.
